(57) **CLAIM**

The ornamental design for a automobile seat cover, as shown and described.

DESCRIPTION

FIG. 1 is a top view of an automobile seat protector.
 FIG. 2 is a bottom view of the automobile seat protector.
 FIG. 3 is a left side view of the automobile seat protector, the right side view being a mirror image;
 FIG. 4 is a front side view of the automobile seat protector; and,
 FIG. 5 is a rear side view of the automobile seat protector. The cross-hatched shading shown in FIGS. 1–4 is understood to cover the surface on which it is applied.
